VALUE-PRINTING APPARATUS

Kurt Aurbach, Bielefeld, Germany, assignor to
 Anker-Werke A. G., Bielefeld, Germany, a corporation of Germany

Application November 19, 1951, Serial No. 257,083

Claims priority, application Germany
 December 1, 1950

9 Claims. (Cl. 101—91)

1

My invention relates to value printing machines in which a value, determined by the setting or operation of adding mechanisms, is printed upon vouchers or other imprintable matter placed against a guiding or feeding device.

It is an object of my invention to provide a value-printing apparatus which permits the use of imprintable matter with a print-receiving surface subdivided into a plurality of areas, and which is capable of separately printing a plurality of impressions upon such a selected individual area of smallest possible dimensions.

To this end, and in accordance with one of the features of my invention, I provide the type-carrying members (type members) and the pertaining counter members (platen members) of the printing apparatus with a connecting transmission of such a ratio that the type members, though performing a plurality of revolutions, can produce only one imprint during the passage of the object to be imprinted.

According to a more specific feature of my invention, I provide a row of mutually spaced, rotary printing devices whose respective printing operations occur sequentially so as to successively place the respective impressions upon the one selected area while the object is passing along the printing devices in the alignment direction of the row; and I further interconnect the type member and the pertaining platen member of each printing device by a transmission whose transmission ratio is different from unity, so that each device produces only one imprint in the proper paper area although its type member performs more than one revolution during a single passage of the paper.

According to another feature of the invention, relating especially to an apparatus with three coordinated printing devices aligned along the path of the object, the above-mentioned transmission between the two coactive members of each device has a transmission ratio of 2:3.

According to a further feature of my invention, the release of the machine and hence the rotation of the printing device is controlled by a feeler engageable by the paper to be imprinted, and this feeler is also designed as a setting device for placing the selected surface area of the print-receiving object into the proper position.

The foregoing and other objectives and features of my invention are apparent from the following description of the embodiment exemplified by the drawing in which:

Fig. 1 is a cross-sectional view of the printing apparatus of a value-printing machine;

2

Fig. 2 is a cross section through part of the same apparatus, the section being taken substantially along the line-denoted by II—II in Fig. 1;

5 Fig. 3 is a view of the feeler and setting device pertaining to the same apparatus, this view taken from the top at the righthand side of Fig. 1;

10 Fig. 4 shows an example of a record sheet of paper or cardboard with a subdivided multiple-entry field, suitable for use with the illustrated machine;

15 Fig. 5 is a vertical sectional view of the apparatus showing the driving transmission of the printing devices;

Fig. 6 shows a cross section along the line VI—VI indicated in Fig. 5 and is a continuation of Fig. 2 when placed at the right-hand side of the latter figure, and

20 Fig. 7 is a separate illustration of details including those apparent in the lower right corner of Fig. 1 and partly also shown in Fig. 3.

25 The illustrated printing apparatus has a housing 1 mounted on a horizontal plate 2 with two rows of openings 3 and 3a (Figs. 1, 2). Located beneath the plate 2 and spaced therefrom a distance corresponding to the thickness of the card, paper or other matter to be imprinted, is another horizontal plate 4 (Figs. 1, 2, 7) with openings 5 and 5a adjacent to the respective openings 3 and 3a of plate 2. Two feed rollers 6 (Figs. 1, 2), mounted on respective hubs 7 (Fig. 2), are disposed beneath each pair of openings 5 and 5a (Fig. 2). The hubs 7 of each roller pair are pinned onto a common shaft 8 (Figs. 2, 1, 5, 6). Three of the feed roller pairs are joined with a revolvable platen member 9 (Figs. 1, 2). Each platen member has a single radial projection (Fig. 1) which extends over only a small portion of the periphery to act as the platen area proper. The remaining pair of feed rollers 6, located at the right-hand side of the apparatus as shown in Fig. 1, is not equipped with a platen member as it cooperates only with a pair of auxiliary feed rollers 6a (Figs. 1, 3, 7).

30 In Figs. 1 and 2 the feed rollers 6 are illustrated in the inactive position. For lifting the feed rollers 6 and platen members 9 to the active position, each of the pertaining shafts 8 is journaled in an arm 10 pivoted on a shaft 11. Each arm has an extension 12 joined with a spring 13 which tends to move the arm counterclockwise (Fig. 1) to the active position. The extensions 12 have respective pins 14 passing through respective elongated holes 16 of a horizontally dis-

placeable control bar 15 (Figs. 1, 5, 6). Fig. 1 shows the control bar 15 in its rest position where it retains the feed rollers 6 and platen members 9 in the inactive, lowered position. As will be further described in a later place, the control bar 15 is actuated by the machine mechanism in such a manner that it moves toward the right (Fig. 1) at the beginning of an individual machine run and returns to the illustrated position at the end of the run. Hence, during the machine operation, the feed rollers and platen members are moved upward to the active position by the force of the biasing springs 13 and then enter through the openings 5 and 5a into the guide way between plates 2 and 4.

The feed rollers 6 and platen members 9 cooperate with respective type members A, B and C (Fig. 1), each consisting of a composite drum structure. Each of these drum structures has two axially spaced feed rollers 17 and 18 (Fig. 2) with intermediately located sets of type wheels. The type wheels 20 of member A (Figs. 1, 2) indicate the amounts to be printed. The type wheels 21 of member B (Fig. 1) denote the calendar date, and the type wheels 22 of member C (Fig. 1) indicate an identifying member. The type wheels 21 and 22 are manually adjustable, for instance with the aid of rotatable buttons such as those shown at 22a in Fig. 2. The type member C is also equipped with a cliche 22a (Fig. 1) adjacent to the type wheels 22. In each type member the pertaining type wheels are revolvable on a shaft, such as shaft 20a in Fig. 2, which extends between the feed rollers 17, 18 of the type member in eccentric relation to the axis of revolution of the type member. Hence, only the selected one type of each type wheel lies at the periphery of the type member at a time and can produce an imprint when it is in the lowermost position and when the platen area of the pertaining platen member 9 is in its uppermost position at the same time.

As will be more fully explained, the platen member and type member of each printing device are actuated by a common drive whose transmission ratio between the two members is 2:3 so that the platen members 9 (Figs. 1, 2) revolve three times while the type members perform only two full revolutions during each machine operation. During this operation, the selected types and the platen area pass only once through coincident positions so that only one impression is made by each printing device.

The types and the cliche are inked by inking rollers 23 (Figs. 1, 2). The inking rollers 23 are journaled in respective arms 24 which are pivoted on stationary pivot pins 24' (Fig. 1) and are biased toward the type members by means of respective springs 25. As the type wheels during the rotation of each type member A, B and C pass by the pertaining inking roller 23, this inking roller comes into engagement with the one type of each type wheel that is to produce an imprint. The type wheels 20 of type member A are joined through concentric tubes 26 (Fig. 2) with respective spur gears 27. The tubes 26 are freely revolvable relative to one another and relative to the shaft 20a, each tube forming a rigid connection between one type wheel and one of the respective gears 27. The gears can be brought into meshing engagement with a set of coaxial and individually revolvable spur gears 28 (Figs. 1, 2) which form part of a transmitting mechanism that comprises for each of gears 28 a train of intermediate spur gears 29, 30, 31 and 32

(Fig. 1). The gears 28 are individually revolvable about a common shaft 28a (Fig. 2). Similarly the sets of gears 29, 30, 31, 32 are revolvable about shafts 29a, 30a, 31a and 32a respectively (Fig. 1).

5 The shafts 28a, 29a, 30a, 31a are all rigidly secured to a pivotally mounted support structure 28b (Figs. 1, 2).

Each of the gear trains 28 to 31 is driven by the pertaining gear 32 (Figs. 1, 2). The gears 10 32 are mounted on respective tubes 32b concentrically seated on shaft 32a and revolvable relative to one another (Fig. 2). Rotary motion is imparted to the tubes 32b from a setting mechanism (not illustrated) of known design as customary for business machines. Such a setting mechanism, suitable for use with the present invention, is illustrated and described in U. S. Patent No. 1,954,694. Latch pawls 33 and 34 (Figs. 1, 2) are provided for securing the gear trains 28 to 31 in the adjusted position. Further 15 latch pawls 35 (Figs. 1, 2) cooperate with the type wheels 20. After the type wheels 20 are adjusted to the amount to be printed, the spur gears 28 are disengaged from the spur gears 27 by shifting the support 28b and with it the gear-train mechanism counterclockwise about a pivot 37 (Fig. 1) so that the spur gears 28 move from the position shown in Fig. 1 to the inactive position shown in Fig. 2. In the latter position, the 20 type member A is free to revolve and has its type wheels so adjusted that the amount to be printed appears on the individual types now located at the periphery. When the support 28b is being 25 shifted in the just-described manner, the spur gears 31 move downwardly out of engagement with the gears 32.

The shifting movement of support 28b is effected by means of a pin 85 which is firmly secured to the support 28b and engages a slot 89 of a lever 88. Lever 88 has a lug 90 entering into a recess 91 of a disc 92 firmly mounted on the main drive shaft 53. Lug 90 and disc 92 lock the main drive shaft as long as the support 28b and its train of gears 28 to 31 are in the illustrated position (Fig. 1). When the lever 88 is turned counterclockwise about its pivot, the support 28b is placed in gear disengaging position and the main shaft 53 is released for subsequent operation of the printing devices A, B, C through the transmission gear means described in the following.

The drum structure of each type member with the pertaining feed roller 18 is seated on and pinned to a shaft 37 (Figs. 1, 2). The shafts 37 are journaled in a side wall portion 37a of the housing and carry respective spur gears 38 (Figs. 5, 6). Two of the spur gears 38 mesh with a larger spur gear 39, while the remaining spur gear 38 is driven through an intermediate spur gear 40. During the operation of the printing apparatus, the large gear 39 is driven to perform one complete counterclockwise revolution (Fig. 5). Since gear 39 has twice the diameter of gears 38, each gear 38 then performs two complete clockwise revolutions. Hence, the shaft 37 of respective type members A, B and C also turn twice clockwise.

The one-revolution gear 39 is mounted on a sleeve 41 revolvable on a stationary bearing pin 42 (Figs. 5, 6). The bearing pin is riveted to a side wall 43 of the housing (Fig. 6). Also mounted on the sleeve 41 are a cam disk 45 and a spur gear 46 (Figs. 5, 6). The sleeve 41 is held on pin 42 by means of a screw 41a. The parts 39, 44, 45 and 46 are rigidly joined with the sleeve 41

by pins 47 (Fig. 6). The spur gear 46 meshes with a spur gear 48 (Figs. 5, 6) which is seated on a hub portion 49 of a further spur gear 50 with which the gear 48 is rigidly joined by screws 51 (Fig. 6). The spur gear 50 is firmly pinned on an extension 52 of a shaft 53 (Figs. 6, 2). Shaft 53 is the main drive shaft so that gear 50 serves as the power input gear of the entire gear transmission.

Three spur gears 54 pinned on three respective shafts 8 (Figs. 5, 6) are in meshing engagement with the spur gears 38 of respective shafts 37. A fourth spur gear 54 on the shaft 8 of the one feed roller 6 that cooperates with the auxiliary feed roller 6a is linked with the adjacent spur gear 54 by an intermediate gear 68 (Fig. 5). As described, each of shafts 8 is journaled near its platen member and feed roller assembly in a pivotally movable arm 19 (Figs. 1, 2) so that this shaft end can be raised and lowered under control by the horizontally displaceable control bar 15. To permit such a shaft movement without interfering with the shaft revolution, the other end of each shaft 8 is journaled in a swivel structure designed as follows.

As shown in Figs. 5 and 6, the swivelled end of each shaft 8 is joined with a bearing sleeve 59. The sleeves 59 are mounted on a frame 55 whose short-side portions are attached to the machine frame structure 58 by means of pivot pins 51. An abutment ring 60 prevents the respective shafts 8 from displacement relative to the frame 55. It will be recognized that by virtue of the swivel bearing, the left portion of each shaft 8 (Fig. 2) may be moved up and down about a pivot point located at the right-hand end (Fig. 6) of the shaft 8 at the point where the pertaining driving gear 54 is located. Consequently, the gear 54 of each shaft is virtually stationarily journaled and remains in meshing engagement with the gear transmission driven from the input gear 49 (Fig. 5).

The control bar 15 (Figs. 1, 5, 6) carries a pin 61 (Figs. 5, 6) straddled by the bifurcated end 62 of a lever 63. Lever 63 is pivotally mounted on a stationary pin 64 and carries a roller 65 which engages the cam disk 45 under the biasing force transmitted to the lever 63 (Fig. 5) by pin 61, slider 15, pins 14 and arms 10 (Fig. 1) from the springs 13. At the beginning of the one full revolution performed by cam disk 45 (Fig. 5) for each machine operation, the roller 65 moves along the cam face toward the cam center so that lever 63 turns counterclockwise about its pivot 64 and shifts the control bar 15 to the right, thus causing the arms 10 (Fig. 1) to raise the feed rollers 6 and platen members 9 into the active position as mentioned previously. At the end of its revolution, the cam disk 45 forces the roller 65 and hence the arm 63 back to the illustrated position (Fig. 5) for retracting the printing devices to the inactive position.

After the type members of the apparatus are set in the above-described manner so that spur gears 31 are disengaged from gears 32 (Fig. 1), and after a voucher or other slip of paper to be imprinted is placed in proper position into the range of the first pair of feed rollers 6 and 6a at the right-hand side of the machine (Fig. 1), the drive for actuating through shaft 53 the gear trains (Figs. 5, 6) of the printing devices A, B, C is ready for operation. This operation may be started in any known manner, for instance, by an operator-controllable push button which controls the energization of an electric motor (not

shown) or effects mechanically or by electric circuit means the closing of a coupling connecting the main drive shaft 53 of the gear transmission with a running motor. In the illustrated apparatus, the drive is released for operation by placing the voucher or other object into the proper position against the first feed roller. To this end, the apparatus has a positioning or lay-on member 70 (Figs. 1, 3) which is designed as a feeler so that its displacement, caused by the laid-on voucher, releases the machine for operation by the above-mentioned drive motor.

The feeler member 70 is pivoted on a pin 71 and has a curved shape so that normally its middle portion enters into one of the openings of the plate 4 (Fig. 1). A shaft 94 (Figs. 1, 7) of the driving mechanism carries a locking disc 93 (Fig. 7) which is normally latched by a locking pawl 95 pivoted at 96 and biased by a soft spring 99. A rod 97 links the pawl 95 with an arm 98 rigidly joined with the feeler 70. When the voucher is inserted beneath the raised free ends of the feeler, it shifts the feeler upwardly thus lifting the pawl 95 from disc 93 thereby releasing the shaft 94 and hence the entire mechanism for operation by the conventional manual crank drive or drive motor. The feeler ends define a frame-shaped opening (Fig. 3) whose dimensions are in accordance with the individual surface areas of the object to be imprinted, such as the entry fields 81, 82 of the receipt card 83 shown in Fig. 4.

Fig. 4 shows in field 81 of card 83 an imprint giving an amount (73.75), a calendar date (17.6.50) and an identifying number (195) printed by the respective type members A, B and C. In addition, the field 81 has a standard impression made by the cliche of type member C. The field 82 is similarly imprinted, except that a different cliche is used.

For causing the previously adjusted printing devices of the apparatus to produce an imprint on any selected field of the card, the operator places the card upon the plate 4 so that the one selected field lies in front of the feeler member 70. By inserting the card, the feeler member 70 is raised and releases the machine for operation. Hence, when the operator now starts the machine drive motor, the cam disk 45 starts rotating and causes the feed rollers to catch the card and advance it through the guide-way slot between plates 4 and 2 to the other side of the apparatus. As the selected entry field of the card passes by the type member A, the amount (73.75) is printed, and as the same field passes by members B and C, the date (17.6.50) and the rest of the impression are sequentially added. The angular position of the type members relative to one another is such that the component prints appear in the desired juxtaposition.

It will be obvious to those skilled in the art that my invention is readily applicable for producing composite prints of any number of component impressions and that it may be modified in various respects and embodied in apparatus other than the one specifically illustrated and described, without departing from the essential features of my invention and within the scope of the claims annexed hereto.

I claim:

1. Value-printing apparatus, comprising a plurality of aligned printing devices each having a revolvable type member and a revolvable platen member, said type member of each device having type elements selectively adjustable, in accordance with the amount to be printed, to a given

place at the periphery of said type member so as to face said platen member of said device only in a given position of revolution of said type member, said platen member having a peripherally limited platen area facing said type member only in a given position of revolution of said platen member so that said two members are in printing condition only when said two positions coincide, feeding means having a guide-way extending along said printing devices and between said two members of each device for passing an object to be imprinted between said members, and drive means having a transmission interconnecting said two members of each device for revolving them simultaneously and in displaced phase relation to said respective two members of each of said other printing devices, said transmission having between the two members of each device a transmission ratio different from unity so that only one impression is produced by each of said devices during a plurality of full revolutions of each member of said device, whereby said object is sequentially imprinted as it passes by said respective printing devices.

2. Value-printing apparatus, comprising a plurality of aligned printing devices each having a type member and pertaining platen means, said type members being revolvable about respective parallel axes transverse to the alignment direction, each of said type members having type elements selectively adjustable to a given place at the periphery of the type member so as to face the pertaining platen means only in a given position of revolution of said type member, said platen means having a revolvable member and having a platen area operatively adjacent to said type member only in a given position of revolution of said revolvable member, feeding means having a guide-way extending between said type member and said platen means for passing therebetween an object to be imprinted, transmission means interconnecting said respective type members with a unity transmission ratio and in phase displaced relation to one another for sequentially imprinting the object as it passes by said printing devices, and transmission means connecting each type member with said revolvable member of the pertaining platen means and having a transmission ratio different from unity so that each device produces only one impression during the passage of the object.

3. Value-printing apparatus, comprising a row of printing devices each having a type member and a platen member both being revolvable about respective parallel axes transverse to the row direction, each of said type members having type elements selectively adjustable to a given place at the periphery of said type member so as to face said platen member only in a given position of revolution of said type member, said platen member having a peripherally limited platen area facing said type member only in a given position of revolution of said platen member so that said two members are in printing condition only when said two positions coincide, feeding means for passing an object to be imprinted between said two members of each of said printing devices, and drive means connected with said feed means and having a first transmission mechanism interconnecting said type members for cooperative rotation at equal speeds and a second transmission mechanism interconnecting each pair of type and platen members for cooperative rotation and having a transmission ratio different from unity, said printing devices being in phase displaced

relation to one another so that each device produces only one impression during the passage of the object.

4. In a printing apparatus according to claim 5 2, said transmission means between each type member and the pertaining platen member having a transmission ratio of 2:3.

5. Printing apparatus according to claim 1, comprising a movable feeler member for start-10 controlling said drive means, said feeler member being disposed at the entrance of said guide-way and having a frame-shaped portion substantially matching the area to be imprinted on the object, said feeler member being engageable by the ob-15 ject to be moved thereby.

6. Value-printing apparatus, comprising a plurality of revolvable type members having respective parallel axes, revolvable platen members co-operatively related to said respective type members, feed means extending along said type members for passing an object to be imprinted between said type members and said platen members, each type member and each platen member having respective peripherally-limited action areas oppo-20 site each other only at coincidence of given revolutionary positions respectively of said two members, bearing structures on which said respective platen members are revolvably mounted, said bearing structures being movable for displacing 25 said platen members toward and away from said type members, stationarily journaled drive gears connected with said respective platen members, transmission means connecting said drive gears with said respective type members for simultaneously revolv-30 ing said type members and said platen members, said transmission means having between said type members and said platen members a transmission ratio smaller than unity and unity transmission ratio mechanism intercon-35 necting said type members for cooperative rotation, said printing devices being in phase displaced relation to one another.

7. Value-printing apparatus, comprising a row

of printing devices, each of said devices having a 45 revolvable type member and a revolvable platen member, said two members of each device having respective peripherally-limited action areas op-50 posite each other only at coincidence of given revolutionary positions respectively of said two members, said type members having respective axes of revolution parallel to each other, feed

means extending along said row of printing devices for passing an object to be imprinted between said type members and said platen mem-55 bers, said feed means having feed rollers adja-60 cent to and coaxial with said respective platen members to revolve together therewith, said platen member and said feed roller of each of said printing devices having a shaft in common, stationary support means forming a pivot and having a pivot

axis transverse to the axis of said shaft, said shaft being movably mounted on said pivot at a point of the shaft spaced from said platen member and feed roller to permit moving said platen mem-65 ber and said feed roller about said pivot axis to-70 ward and away from said type member, transmission means connecting each of said shafts at said respective points with said respective type

members and having a transmission ratio different from unity and unity transmission ratio mechanism interconnecting said type members for cooperative rotation, said printing devices being in phase displaced relation to one another.

comprising spring means connected with said respective bearing structures and biasing said bearing structures and said platen members toward said respective type members, a control element engaging said respective bearing structures for holding said platen members away from said type members in opposition to said spring means, said control element being movable to a position in which said spring means are released for moving said platen members toward said respective type members, and drive means connected with said transmission means and with said control element for operating them in a given relation to each other.

9. In combination with printing apparatus according to claim 1, said object to be imprinted consisting of a sheet having a multiplicity of fields, all of the same size, to be selectively imprinted, and said drive means comprising a feeler member for start-controlling said drive means, said feeler member being disposed at the entrance of said guide-way and being operable by engage-

ment with said sheet being inserted, said feeler member being frame-shaped and having a frame opening of substantially the same size as said individual fields to serve as a lay-on device for selecting the one field to be imprinted at a time.
